PROCESSES FOR THE PRODUCTION OF DIBASIC AND MONOBASIC ACIDS

Allison Maggiolo, Merion, Pa., assignor to The Welsbach Corporation, Philadelphia, Pa., a corporation of Delaware

No Drawing. Application March 6, 1956
 Serial No. 569,673

3 Claims. (Cl. 260—406)

This invention relates to processes for the production of dibasic and monobasic acids and more particularly to such processes in which an unsaturated fatty acid is ozonized and the resulting ozonide oxidized to obtain the acids.

More particularly still this invention relates to such processes in which the ozonolysis of the unsaturated fatty acids is conducted at carefully controlled lower temperatures in the presence of water and the following oxidative decomposition of the ozonide is carried out at carefully controlled higher temperatures in the presence of water.

This application is a continuation-in-part of my application Serial No. 522,395, filed July 15, 1955, and now abandoned.

Processes for the production of carboxylic acids by the ozonolysis of an unsaturated fatty acid followed by oxidative decomposition of the ozonides are known and in particular the German Patent No. 565,158 of March 20, 1931, to Alfred Rieche discloses a process in which simultaneous ozonolysis and oxidation at elevated temperatures of unsaturated fatty acids produces dibasic and monobasic acids without excessive consumption of ozone. In this German patent temperatures up to 150° C. are employed.

British Patent No. 741,739 of December 14, 1955 disclosed a two-step procedure in which an unsaturated nitrile is first ozonized and the ozonides are then decomposed and oxidized using water and molecular oxygen.

The generally accepted practice in the art has been to avoid the presence of water in ozonolysis reactions. Various theories have been advanced to support this practice. Many publications allege that the presence of water during ozonolysis causes undesirable end products. Pertinent examples are:

(1) Certain ozonides can decompose in two ways as a result of the presence or absence of water, see Briner, *Helv. Chim. Acta* 21, p. 748 (1938).

(2) Ozonides containing oxygen in other parts of the molecule react readily, in almost every case, even with ice water, see Long, *Chem. Rev.*, 27 p. 3 (1940).

(3) Ozonides of relatively high molecular weight have been known to resinify when heated with water, *ibid.*

(4) Ozonides of unsaturated ketones and aldehydes can be continuously decomposed after formation by drawing a stream of moist air through the ozonized solution; see Straus, *Ann.* 393, p. 235 (1912).

(5) A proposed mechanism of ozonide decomposition which begins with the presence of water has been shown by Harries, *Ann.* 374, p. 288 (1910).

Most unexpectedly I have found that the presence of water in the ozonolysis of unsaturated fatty acids does not adversely affect the yield of carboxylic acids obtained therefrom.

I have found further and most unexpectedly that if the ozonolysis of the unsaturated fatty acid is conducted at temperatures in the range of 0–49° C. and preferably in the range of approximately 15–30° C. in the presence

5 of water and, thereafter, if the ozonides are oxidized at higher temperatures above 100° C. and up to 150° C. in the presence of water and ozone a very significant increase in the amount of acids produced is obtained, on the order of from 15 to 20%.

10 Considerable heat is evolved in the ozonolysis of unsaturated compounds. In particular, it has been established with respect to the present type of reaction that approximately 110 K Cal. per mole of unsaturation is liberated, see Briner et al., *Helv. Chim. Acta* 21 p. 357–363 (1938). Considerable effort has heretofore been required to provide proper external cooling of reactions of ozone with unsaturated compounds. Cooling devices well known in standard chemical engineering practices have been employed. In accordance with the present invention the necessary cooling is internal and is provided by the water mixed with the reactants.

15 It is accordingly an object of the present invention to provide novel processes for the production of carboxylic acids in which water is employed in the ozonolysis of unsaturated fatty acids to increase the yield of carboxylic acids.

20 Another object of the present invention is to provide novel processes for the production of dibasic and monobasic acids from unsaturated fatty acids in which the unsaturated fatty acids are first ozonized at temperatures in the range of 0–49° C. and preferably in the range of approximately 15–30° C. in the presence of water and ozone until the production of ozonides is completed and then subjecting the ozonides to oxidative decomposition at temperatures of approximately 100° C., and up to 150° C., in the presence of water to obtain increased and improved production of the acids.

25 Another object of the present invention is to provide such novel processes in which water is employed with the reactants in the ozonolysis step to remove the heat of reaction.

30 Other and further objects of the present invention will appear from the following description of illustrative embodiments thereof.

35 These illustrative embodiments of the present invention are described below for purposes of illustration only and should in no way be construed as defining or limiting the invention, reference being had to the appended claims to determine the scope thereof.

40 As noted above, the processes of the present invention include as a first step for the production of carboxylic acids the ozonolysis of unsaturated fatty acids in the presence of water and as a following step the oxidative decomposition of the resulting ozonides also in the presence of water. The ozonization step is performed by passing an ozone-oxygen or ozone-air mixture into the unsaturated fatty acid at low temperatures with added water. The unsaturated fatty acid is usually dissolved in an inert solvent. The resulting ozonide is not isolated and is used directly in the oxidative decomposition step. To perform the oxidative decomposition step oxygen, air, or a suitable chemical oxidant is added to the ozonide with added water, if required, and at an elevated temperature and using an oxidation catalyst which may be water or ozone or both. When the ozonolysis is carried out at temperatures in the range of approximately 15–30° C. and the following oxidative decomposition step is carried out at higher temperatures up to 150° C. an unexpected increase in the amount of acids produced is obtained as will more fully appear hereinafter.

45 The experimental results of Table I show that the yield of dibasic acid is not adversely affected by the presence of water in the ozonolysis step. When water is present in amount equal to the unsaturation and solvent, some increase in yield is obtained. When the weight of water is 5 to 6 times the unsaturation and solvent during

ozonolysis, the yield is decreased by only 3 to 4%. These losses were probably caused by the relatively large volumes handled on a laboratory basis and would not be expected on plant scale quantities.

Table I also shows that external cooling must be provided to maintain the reactor temperature at 30° C. when the water content is 20% or less. However, when water is present in the range from approximately 100 to 600% no external cooling is necessary, and the temperature of the reactor did not exceed 46° C.

TABLE I
Ozonization of tall oil fatty acid in caproic acid

1.....	95	246	78.6
1.....	570	240	73.3

¹ Water content based on total unsaturate plus solvent.

² No external cooling.

In accordance with one embodiment of the processes of the present invention tall oil unsaturated fatty acids, comprising approximately equal proportions of oleic and linoleic acids, were ozonized at controlled temperatures in the range of approximately 15-30° C. in the presence of water and this reaction may be expressed by the following equations:

These ozonides were then subjected to oxidative decomposition in the presence of water as expressed by the following equations:

Little or no malonic acid is formed although the formation of this acid might be expected and the disposition of the three-carbon linkage between the two ozonide groups is therefore unknown.

More specifically, in the process described above 56 g. (0.20 moles) (0.30 equivalent of double bond) tall oil unsaturated fatty acids (U. F. A.) in solution in 60 gm. of caproic acid is placed in a cylindrical glass vessel having a fritted glass bottom and connected at the top to a cold finger condenser, an absorber containing 100 ml. of 5% aqueous potassium iodide solution, and a wet test meter in series. Calculated amounts of water up to 600% by weight of the reactants and solvent are added so that the reaction in the glass vessel can be conducted

at a controlled temperature in the range of approximately 15-30° C. Ozonolysis is then carried out by admitting a stream of oxygen containing approximately 1-6% ozone by weight to the glass vessel through the fritted plate at approximately 0.050 C. F. M. for approximately three hours and until the iodide test solution turns red-brown indicating the presence of ozone and an essentially completed reaction.

The ozone concentration is then reduced to $\frac{1}{10}$ to $\frac{3}{10}\%$ without interruption to the oxygen stream which may be reduced to 0.01 C. F. M. and oxidation of the ozonides in the glass vessel is continued for approximately three and a half hours. During this oxidation step the temperature in the glass reaction vessel should be raised to approximately 100-110° C. by heating coils surrounding the glass vessel.

At the end of the oxidation step the mixture in the glass vessel is cooled and transferred to a distilling flask where it is distilled at 15-20 mm. Hg. The fraction of monobasic acids distilling at 60-160° C. amounting to 81.5 g. are chiefly caproic and pelargonic acids.

The stripped residue is then boiled and the resulting aqueous layer separated from the oily layer. The cooled aqueous solution deposits almost pure azelaic acid, neutral equivalent 95-96. Azelaic acid should also be extracted from the oily layer and the total yield of almost pure azelaic acid approximates 70%. An inferior grade of crude azelaic acid amounting to approximately 10-15% may be isolated from the mother liquors. The yield of almost pure azelaic acid in accordance with this embodiment of the present invention reflects an improvement of approximately 15% over previous known methods and particularly that of German patent.

Oxidants other than oxygen or air may be used to advantage in this process as shown in Table II:

TABLE II
Oxidation of tall oil fatty acid ozonide comparison of different oxidants

¹ Based on theoretically obtainable dibasic acid.

² Best run.

³ $\frac{1}{10}$ to $\frac{3}{10}\%$ percent by weight.

Table II shows that when ozone in amounts of from $\frac{1}{10}$ to $\frac{3}{10}\%$ by weight is present in the oxidizing gas the yield of dibasic acid is improved.

Comparing the processes of the present invention more specifically with those of the German patent the procedure of this patent was followed in detail with a mixture of oleic acid, water and acetic acid which was ozonized at 60° C. with a yield of 60% high-grade azelaic acid. An identical mixture was then treated in accordance with the present invention and was ozonized at 25° C. in the presence of water until one mole of ozone per mole of unsaturation had been added. The temperature was then raised during the oxidative decomposition step and the reaction was completed in the manner described in the German patent again in the presence of water. A yield of 70% high-grade azelaic acid was obtained.

The same procedure, as above, was carried out utilizing tall oil fatty acids, caproic acid, and water which were ozonized at 70° C. in accordance with the German patent producing a yield of 63% high-grade azelaic acid.

An identical mixture was treated at 90° C. in accordance

with the German patent and produced a yield of 34.4% high-grade azelaic acid. An identical mixture was then treated in accordance with the processes of the present invention and ozonized at 20° C. in the presence of water until one mole of ozone per mole of unsaturation had been added. Thereafter the temperature was raised into the range taught by the German patent during the oxidation decomposition step and the reaction was completed in the presence of water with a yield of 70.5% high-grade azelaic acid.

It will now be apparent to those skilled in the art that the present invention provides novel processes for the production of dibasic and monobasic acids including the ozonolysis of unsaturated fatty acids at low temperatures in the presence of water followed by oxidative decomposition of the ozonides at high temperatures in the presence of water and ozone in the oxidizing gas to provide improved production of the acids and control of the ozonolysis reaction temperatures which in every way satisfy the objects described above.

Changes in or modifications to the illustrative embodiments of the processes of the present invention described above may now be suggested to those skilled in the art without departing from the present inventive concept. Reference should therefore be had to the appended claims 25 to determine the scope of the invention.

What is claimed is:

1. In a process for the production of dibasic and monobasic acids from unsaturated fatty acids selected from the group consisting of oleic acid, linoleic acid and mixtures of oleic acid and linoleic acid in a solvent, the steps of ozonizing the unsaturated fatty acids in the presence of an amount of water in the approximate range of one to six times by weight of the unsaturated fatty acid and solvents, subjecting the resulting ozonides to oxidative decomposition in the approximate temperature range 100-150° C. and then extracting the acids.

2. In a process for the production of dibasic and monobasic acids from unsaturated fatty acids selected from the group consisting of oleic acid, linoleic acid and mix-

tures of oleic acid and linoleic acid the steps of ozonizing the unsaturated fatty acids in the presence of water in amounts sufficient to maintain the temperatures of reaction in the approximate range of 0-49° C., the amounts of water falling in the approximate range of from one to six times by weight of the unsaturated fatty acids and solvents, subjecting the resulting ozonides to oxidative decomposition in the approximate temperature range 100-150° C. and then extracting the acids.

3. In a process for improving the yield in the production of dibasic and monobasic acids from unsaturated fatty acids selected from the group consisting of oleic acid, linoleic acid and mixtures of oleic acid and linoleic acid, the steps of ozonizing the unsaturated fatty acids in the presence of an amount of water in the approximate range of one to six times by weight of the unsaturated fatty acids at reaction temperatures in the approximate range of 40-49° C. and solvents subjecting the resulting ozonides to oxidative decomposition in the approximate temperature range 100-150° C. employing a gaseous oxidant selected from the group consisting of air, mixtures of air and ozone, and mixtures of oxygen and ozone, and then extracting the acids.
